(57) **CLAIM**

The ornamental design for a flight simulator frame, as shown and described.

DESCRIPTION

FIG. 1 is a top view of a flight simulator frame in a first operable configuration;

FIG. 2 is a bottom view of a flight simulator frame in a first operable configuration;

FIG. 3 is a left side view of a flight simulator frame in a first operable configuration;

FIG. 4 is a right side view of a flight simulator frame in a first operable configuration;

FIG. 5 is a front view of a flight simulator frame in a first operable configuration;

FIG. 6 is a rear view of a flight simulator frame in a first operable configuration;

FIG. 7 is a top, front perspective view of a flight simulator frame in a first operable configuration;

FIG. 8 is a bottom, front perspective view of a flight simulator frame in a first operable configuration;

FIG. 9 is a top view of a flight simulator frame in a second operable configuration;

FIG. 10 is a bottom view of a flight simulator frame in a second operable configuration;

FIG. 11 is a left side view of a flight simulator frame in a second operable configuration;

FIG. 12 is a right side view of a flight simulator frame in a second operable configuration;

FIG. 13 is a front view of a flight simulator frame in a second operable configuration;

FIG. 14 is a rear view of a flight simulator frame in a second operable configuration;

FIG. 15 is a top, front perspective view of a flight simulator frame in a second operable configuration; and,

FIG. 16 is a bottom, front perspective view of a flight simulator frame in a second operable configuration.
